DESIGN FOR A WALL SHELF

William Y. Farrah, Kansas City, Mo.

Application December 12, 1938, Serial No. 81,718

Term of patent 3½ years

To all whom it may concern:

Be it known that I, William Y. Farrah, a citizen of the United States, residing at Kansas City, in the county of Jackson and State of Missouri, have invented a new, original, and ornamental Design for Wall Shelves, of which the following is a specification, reference being had to the accompanying drawing, forming a part thereof.

Fig. 2 is an edge elevational view thereof, on a reduced scale.

I claim:

The ornamental design for a wall shelf, as shown.

WILLIAM Y. FARRAH.
